2 Sheets—Sheet 2.

W. SCOTT.

SHEET DELIVERY APPARATUS FOR PRINTING MACHINES.

No. 398,544.

Patented Feb. 26, 1889.

UNITED STATES PATENT OFFICE.

WALTER SCOTT, OF PLAINFIELD, NEW JERSEY.

SHEET-DELIVERY APPARATUS FOR PRINTING-MACHINES.

SPECIFICATION forming part of Letters Patent No. 398,544, dated February 26, 1889.

Application filed August 25, 1886. Serial No. 211,788. (No model.)

To all whom it may concern:

Be it known that I, WALTER SCOTT, of Plainfield, in the county of Union and State of New Jersey, have invented an Improvement in Sheet-Delivery Apparatus for Printing-Machines, of which the following is a specification.

In sheet-delivery apparatus in which the web, after it has been printed in a press, is 10 perforated the ends of the paper are rough and uneven, and in pulling one sheet away from the next there is risk of the sheet becoming slightly misplaced.

The object of the present invention is to 15 deliver the sheet with reliability after the same has been entirely separated from the web, and also to impose one sheet upon the other, so that the edges of the sheets will coincide, thereby adapting the delivery apparatus 20 to book and job work as well as to newspapers.

In the drawings, Figure 1 is a vertical section of my improvement at and near the line *xx* of Fig. 2, and Fig. 2 is a plan view with 25 the upper or mail-cutting cylinder and some of the pulleys and belts removed.

The web of paper that is to be cut up into sheets passes at 2 in between the cylinders 3 and 4. The upper cylinder, 3, is provided 30 with the cutting-blade 5. This blade is preferably received into a longitudinal groove between two supports—usually slats of hard wood—the surfaces of which coincide with the surface of the cylinder, and this knife 35 should have a sharp finely-serrated edge. In the lower cylinder, 4, is a similar longitudinal groove receiving the slats of hard wood, 6, having a channel for the reception of the edge of the cutter 5, and these parts are made 40 so that the web will be entirely separated by the action of the cutter.

The sheets pass away as hereinafter described; but it is necessary that the advancing end of the sheet should follow downwardly 45 upon the surface of the cylinder 4, instead of adhering to the knife 5 and passing up on the surface of the cylinder 3. To effect this object, I use small impaling-pins 7 close behind the opening in slats 6 in the female cutting-50 cylinder 4, so that these pins 7 will hold the advancing end of the sheet sufficiently to carry it downwardly.

There are bridge-bars 8 extending from the cross-bearer 9 to the surface of the cylinder 4, and these bridge-bars are preferably at an 55 inclination so that the sheet will run down the same from the cylinder 4. The ends of the bridge-bars, if they rested only upon the surface of the cylinder 4, might not pass in between the cylinder and the sheet. To prevent this difficulty I turn in the surface of the cylinder 4 several narrow grooves, 10, and I make the bridge-bars preferably of L-shaped sheet metal, so that the vertical portion of the sheet metal of the bridge-bar passes into 60 the groove, the end of the bridge-bar being shaped to conform to the bottom of the groove, and the pins 7 should be adjacent to these grooves, so that the ends of the bridge-bars within the grooves act to lift the end of the 65 sheet directly off the pins, so that the sheet may pass down the bridge-bars and in between the belts next described.

The ranges of belts or tapes 12 and 13 are 70 of any suitable material, and at proper distances apart. They pass around the sectional rollers 14 and 15, and are led over the sectional guide-cylinder 16, the belts 13 passing around the roller 17, over the roller 18, and around the rollers 19 and 20, back to the roller 15, the 75 rollers 18, 19, and 20 illustrating portions of an ordinary folding mechanism or other suitable sheet-delivery apparatus. The belts 12, after passing around the guide-cylinder 16, 80 pass down and beneath the imposing-cylinder 22, up against the roller 17, over the roller 18, and around the rollers 23, 24, and 25, back to the roller 14.

The rollers 20 and 25 are represented as 85 adapted to tightening the belts, and it is to 90 be understood that the arrangement of the rollers 18 19 20 23 24 25 may be varied according to the folding or delivering mechanism with which the present improvements are employed.

The guides 30 are supported by the bearer 31. The under surfaces of such guides are 95 curved to correspond to but are at a slight distance from the surface of the imposing-cylinder 22, and the sides of such guides correspond to and are at a slight distance from the sectional guide-cylinder 16, and it will 100 now be apparent that the advancing end of the web of paper is directed by the bridge-

bars 8 in between the ranges of tapes 12 and 13; but the sectional rollers 14 and 15 must be sufficiently far apart not to nip the sheet, because the tapes or belts 12 and 13 will usually travel at a faster speed than that of the web of paper. When the advancing end of the sheet reaches the sectional guide-cylinder 16, it will be nipped between the belts and move at the same speed as such belts, 10 and the curved guides 30 direct the sheet and cause it to pass down and around the guide-cylinder 16 along with the belts 12, and then such sheet will pass in between the belts 12 and the imposing-cylinder 22, and be carried 15 by and with such belts 12 until they leave the imposing-cylinder 22 and pass up against the rollers 17.

If now one or more sheets are to be imposed upon the cylinder 22, the advancing end 20 or ends of such sheet are to be passed in beneath the curved guide 30, and the parts are so timed that the second sheet passing around the guide-cylinder 16 comes up to and the end coincides with the advancing end of the first 25 sheet as the two sheets pass between the guide-cylinder 16 and the imposing-cylinder 22. In this manner two or more sheets 30 can be imposed with accuracy, so that their edges coincide. When the sheet or sheets 35 are to be passed off the imposing-cylinder 22 to the roller 17, I find in practice that usually the spring of the paper, the action of the atmosphere, or the electric condition is sufficient to cause the advancing end of 40 the sheet or sheets to follow and lie against the tapes 12; but to prevent the advancing end adhering to the cylinder 22, I provide the discharge-fingers 40 upon the shaft 41, having a spring, 42, that acts to close the fingers toward the cylinder, and an arm, 43, that 45 is acted upon by a cam, 44, to cause the fingers to force the sheet from the cylinder 22 against the belts 12. This cam 44 is on an eccentric, 47, and rod 48, the eccentric being 50 upon a shaft, 49, that is revolved once to every two revolutions of the cutting-cylinder 3, so that the cam 44 is brought into action every two sheets that are imposed upon the cylinder 22. If three or more sheets are to be gathered upon the cylinder 22, the shaft 49 will be revolved once in every three or more revolutions of the cylinder 3.

The curved shields 50 are upon the shaft 55 51, and they are drawn back by the spring 52, and retained in a normal position outside of the path of the tapes 12, and are swung toward the imposing-cylinder 22 by the cam 52 and rod 53, and these shields are placed so as 60 to pass in between the belts 12, and the con-

cave surfaces of such shields coincide with but are at a slight distance from the cylinder 22. The parts are so timed that the curved shields 50 are brought up toward the imposing-cylinder 22 at the proper time to guide the 65 advancing end of the first sheet around upon the surface of the imposing-cylinder 22, and cause it to pass in beneath the curved guides 30 to meet the second sheet as it passes over the cylinder 16 and between the same and the 70 imposing-cylinder 22, and when the sheets are to be delivered by the fingers 40 the shields 50 are drawn back out of the way by the spring 52.

The rod 53 should be hook-ended, so that it 75 may be disconnected from the arm 60 or from the shaft 51, in which case the sheets will pass around the imposing-cylinder 22, and each sheet will be delivered separately.

I remark that the ends of the curved guides 80 30 next to the shields 50 should be rounding, to insure the passage of the sheets beneath them, and the upper ends of the shields 50 should lap past the lower ends of these guides 30. 85

I claim as my invention—

1. The combination, with the imposing-cylinder 22 and the rollers 16 and 17, and tapes for bringing the sheets to such imposing-cylinder, of the guides 30, with curved faces adjacent 90 to the cylinder 22 and roller 16, and the curved shields 50, cross-shaft 51 for supporting such shields outside the path of the tapes, and mechanism for moving the shields intermittently toward and from the imposing-cylinder, whereby alternate sheets are caused to 95 pass beneath the guides 30, and the pairs of imposed sheets are delivered on the belts 12, substantially as set forth.

2. The combination, with the imposing-cylinder 100 22 and the rollers 16 and 17, and tapes for bringing the sheets to such imposing-cylinder, of the guides 30, with curved faces adjacent to the cylinder 22 and roller 16, and the curved shields 50, and cross-shaft 51 for supporting 105 the same outside the path of the tapes 12 and the delivery-fingers 40, and mechanism, substantially as specified, for moving the delivery-fingers and segmental shields alternately for the latter to direct one sheet in beneath 110 the segmental guides 30 and then for the delivery-fingers to cause the two sheets to follow the belts 12 to the rollers 17, substantially as specified.

Signed by me this 20th day of August, A. 115 D. 1886.

WALTER SCOTT.
